UNITED STATES PATENT OFFICE.

DARIUS BABCOCK, OF MERIDEN, CONNECTICUT.

CHAIN-GUIDING MECHANISM FOR TENTERING-MACHINES.

SPECIFICATION forming part of Letters Patent No. 469,221, dated February 23, 1892.

Application filed August 24, 1891. Serial No. 403,530. (No model.)

To all whom it may concern:

Be it known that I, DARIUS BABCOCK, a citizen of the United States, residing at Meriden, in the county of New Haven and State of Connecticut, have invented certain new and useful Improvements in Chain-Guiding Mechanism for Tentering-Machines; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 In the accompanying drawings, Figure 1 represents a plan view of a section of a chain and guide-rail, and also the adjusting-brackets, and serves well to illustrate the spirit and scope of my invention. Fig. 2 is a transverse 20 sectional view taken through the line X, Fig. 1.

This invention relates to improvements in that class of tentering-machines in which the fabric is stretched between two chains, which travel at a uniform rate of speed and operate 25 one on each side of the machine. It is most closely allied to that class of tentering-machines which are employed for the manufacture of shade-cloth, but, as will be readily understood, can be used with equal advantage 30 upon the ordinary drying-machines.

The object of this invention is to provide a simple, cheap, durable, and efficient means for guiding the chain, which at the same time shall permit of ready and easy adjustment in 35 setting up or building the machine or straightening the rail when the occasion requires.

Heretofore machines of a similar character have been provided with solid brackets admitting of no adjustment, therefore causing 40 great difficulty in the erection of the machines and otherwise proving unsatisfactory. The brackets being mounted upon a wooden frame, which, owing to its susceptibility to the changes of the atmosphere—*i. e.*, dryness and dampness—the rail soon became out of true, with 45 no means of straightening it, thereby often causing serious damage to the production of the machine, since in this class of machines it is of the utmost importance that the chains 50 should run perfectly parallel with each other in order to produce perfect goods.

In the drawings, A is a bracket, which is fastened to the frame-work of the machine, and a is a roll mounted therein and over which the chain passes when in motion.

55

B represents the studs or rivets by which the side bars of the links are secured together.

C is a bracket secured to the inside of one of the side bars, and c is a roll mounted in the same. On the outside of the opposite side 60 bar is secured the tenter-hooks, (designated by the letter D.) An arm or bracket E is secured to the top of the bracket A by means of a screw-threaded bolt, which passes through the elongated slot e in the bracket E. The 65 guide-rail G is secured in any well-known manner to the outer end of the bracket E, as shown. It is obvious that the guide-rail may be easily and readily straightened, should it from any cause whatever become out of true, by simply 70 loosening the bolt F and moving the bracket transversely in the proper direction and again securing it in place by tightening the bolt or screw.

The operation of the device is as follows: 75 When the cloth is stretched between the chains, they are drawn toward the center of the machine until the rolls c engage or contact with the guide-rail G. Therefore it will be seen that unless the guide-rails are perfectly parallel the cloth would become stretched at certain points when drying, thereby causing serious damage to the production, all of which can be quickly and perfectly remedied by the use of the adjustable guide-rail in the 80 manner hereinbefore described. Therefore, 85

Having thus described my invention, what I claim, and desire to secure by Letters Patent, is—

1. As an improvement in chain-guiding 90 mechanism for tentering-machines, the combination, with a bar-link sprocket-chain, the outer links of which are provided with inwardly-projecting rolls, of a horizontal guide-track projecting downwardly between the inner links of the chain and the rolls and forming a bearing-surface for the latter, and brackets carrying said track and provided at their secured ends with an elongated slot through 95 which the securing-bolt is passed, substantially as and for the purpose set forth.

2. As an improvement in chain-guiding

mechanism for tentering-machines, the combination, with supporting-brackets A, formed with an approximately-U-shaped arm, rolls a, journaled in the vertical portions of the latter, overhanging brackets E, arranged parallel with the brackets A and provided in their secured ends with an elongated slot e, adapted for the reception of a securing-bolt for binding the brackets A and E together, and a horizontal track G, secured to the free overhanging ends of the brackets E and depending

therefrom, of a bar-link sprocket-chain supported upon the rolls a, and rolls c, carried by the outer links of the chain and adapted to bear against the track, substantially as and for the purpose set forth. 15

In testimony whereof I affix my signature in presence of two witnesses.

DARIUS BABCOCK.
